US0D1007002S

(12) **United States Design Patent** (10) **Patent No.:** **US D1,007,002 S**
(45) **Date of Patent:** **** Dec. 5, 2023**

(54) **LID FOR A REAGENT CARTRIDGE**

(71) Applicant: **Singular Genomics Systems, Inc.**, La Jolla, CA (US)

(72) Inventors: **Bandele Jeffrey-Coker**, Darnestown, MD (US); **Eli N. Glezer**, Del Mar, CA (US); **Anson Hsu**, San Diego, CA (US); **Cory Spivey**, San Diego, CA (US)

(73) Assignee: **Singular Genomics Systems, Inc.**, San Diego, CA (US)

(**) Term: **15 Years**

(21) Appl. No.: **29/869,464**

(22) Filed: **Dec. 30, 2022**

Related U.S. Application Data

(63) Continuation of application No. 29/837,498, filed on May 5, 2022, now Pat. No. Des. 979,093.

(57) **CLAIM**

The ornamental design for a lid for a reagent cartridge, as shown and described.

DESCRIPTION

FIG. 1 is a front, top, and right side perspective view of a lid for a reagent cartridge of our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash broken lines illustrate portions of the lid for a reagent cartridge that form no part of the claimed design.
